G. LOOPER

TEMPERATURE INDICATOR FOR RADIATORS

Filed Sept. 23, 1922

FIG. 1.

FIG. 2.

FIG. 3.

Glenn Looper

Watson E. Coleman
Attorney

UNITED STATES PATENT OFFICE.

GLENN LOOPER, OF BALTIMORE, MARYLAND.

TEMPERATURE INDICATOR FOR RADIATORS.

Application filed September 23, 1922. Serial No. 590,097.

This invention relates to temperature indicators for radiators, tanks and the like, and an important object of the invention is to provide an improved structure of this type in which the tube containing the indicating fluid is fully protected against accidental breakage.

A further object of the invention is to provide a construction of this character in which the tube of the indicator does not extend into the tank or radiator to which the indicator is applied.

A still further object of the invention is to provide a construction of this character which is extremely simple and which accordingly may be cheaply and expeditiously produced and which at the same time will be practical, durable and efficient in service.

These and other objects I attain by the construction and arrangement shown in the accompanying drawings wherein for the purpose of illustration is shown a preferred embodiment of my invention and wherein like reference characters designate like parts throughout.

In the drawings:

Figure 1 is a vertical sectional view taken through a temperature indicator constructed in accordance with my invention, showing the same applied to the cap of a tank;

Figure 2 is a transverse sectional view through the form of indicator shown in Figure 1; and

Figure 3 is an enlarged sectional view showing the manner of mounting the lenses in the bezel frame and of securing the upper end of the indicating tube against movement.

Referring now more particularly to the drawings, the numeral 10 indicates a base adapted for engagement with the outer surface of a tank T about the opening 11 formed therein, or with the outer surface of a cap C closing the opening in the tank and having an opening 11. The base 10 has formed therein a bore 12 opening through the lower end of the base and adapted to communicate with the opening 11. The upper wall of the bore of the base has depending therefrom a boss 13 which has formed therein a bore 14. The bore 14 of the boss extends through the upper end of the base and is adapted for the reception of the lower end of a tube 15 containing a thermo active fluid.

Formed integrally with the upper surface

of the base and extending upwardly therefrom is a bezel frame 16 of any desired outline and of sufficient size to accommodate the length of tube 15 employed, the upper end of the tube 15 extending into proximity to the upper end of the bezel frame. A retaining element 17 embraces the upper end of the tube and has its ends secured, as at 18, to the bezel frame and serves to hold the upper end of the tube against vibratory movement tending to destroy the same. The bezel frame 16 has formed in the side faces the lens-receiving grooves 19 in which the lenses 20 are held in position by means of clamping wires 21 or the like.

As means for securing the base 10 in position upon the tank with the bore 12 thereof in alignment with the opening 11, I provide a retaining element 22 adapted to abut the inner face of the wall of the tank about the sides of the opening 11 and having threaded engagement with the base 10 whereby the retaining element may be moved toward or away from the base 10 to coat therewith to clamp the base against the tank or cap. It will be understood that in referring to the tank wall, this reference includes the walls of the cap which form a portion of the tank wall when employed as a closure for the opening formed in the tank. The retaining element 22 is shown as provided with an upwardly extending flange 23 fitting within the opening 11 of the tank or cap and within the bore 12 of the base 10. The upper end of this flange is provided with an inwardly extending shoulder 24, the inner face of which is screw-threaded for coaction with the boss 13 which is externally screw-threaded. The retaining element 22 is preferably in the form of a nut and it will be seen that upon relative rotation of the retaining element and base the threaded engagement of the shoulder 24 with the boss 13 will cause the base and retaining element to move toward or away from one another, dependent upon the direction of rotation.

In order to prevent movement of the tube 15 within the bore 14 of the boss 13, this boss is provided at its lower end with means 27 preventing downward movement of the tube and the upper end of the bore is slightly enlarged, as indicated at 28, and the space between the tube 15 and the walls of the bore filled with cement 29 preventing upward movement of the tube. The retaining

means at the lower end of the boss 13 preferably take the form of a nut shown in Figure 1.

If desired, the retaining element 17 employed for steadyng the upper end of the tube 15 may form a support for plates 30 arranged at opposite sides of the tube 15 between and discernible through the lenses 20. The faces of these plates 30 may be provided 10 with any suitable indicia, such as wording or coloring, or scale numerals by means of which the condition of the fluid contained in the tube may be determined by comparison of this scale indicia or coloring with the condition or position of the fluid within the tube 15. For example, if the fluid be one of that order changing color in response to variations of temperature, the plates 30 may be provided at a suitable point with coloring 20 of that shade which the liquid within the tube assumes when the water within the radiator boils; at another point with the normal coloring of the liquid; and between these two points with a graduated chromatic 25 scale showing the various conditions as represented by the corresponding colors of the liquid. Since, however, such liquid need not be employed, I do not limit myself to this construction and have not accordingly here- 30 in illustrated the same beyond the showing of the plates 30 as carried by the element 17 and as positioned upon opposite sides of the tube. The means employed in securing the plates 30 to the element 17 may be of any 35 desired type, in the present instance these plates being shown as attached thereto.

From the foregoing it will be seen that the tube 15 is fully protected throughout its length, and that accordingly the tube is very 40 unlikely to be broken and at the same time the bore 12 permits the heat of the tank to circulate about the tube at the lower end thereof sufficiently to heat this lower end to the temperature of the contents of the tank. 45 It will furthermore be obvious that the structure hereinbefore recited is capable of many changes and modifications without materially departing from the spirit of my invention and I accordingly do not limit myself to the specific structure thereof except as hereinafter claimed.

I claim:—

1. In a temperature indicator for radiators and the like, the combination with a radiator having an opening formed in the wall thereof, of a base abutting the outer face of the radiator wall about the opening and having a bore opening into the bottom thereof and communicating with the opening of the radiator wall, a boss depending from the upper wall of the bore of the base, said boss having a bore formed therein opening through the upper end of the base, an indicating fluid containing tube having its lower end disposed in the bore of said boss,

removable means at the lower end of the boss limiting downward movement of the tube in the bore, a protecting housing for the upper end of said tube carried by said base, and means for securing said base in position upon the wall of the radiator inseparable from the base until said removable means is removed.

2. In a temperature indicator for radiators and the like, the combination with a radiator having an opening formed in the wall thereof, of a base abutting the outer face of the radiator wall about the opening and having a bore opening through the bottom thereof and communicating with the opening of the radiator wall, a boss depending from the upper wall of the bore of the base, said boss having a bore formed therein opening through the upper end of the base, an indicating fluid containing tube having its lower end disposed in the bore of said boss, removable means at the lower end of the boss limiting downward movement of the tube in the bore, a projecting housing for the upper end of said tube carried by said base, means for securing said base in position upon the wall of the radiator, including a retaining element arranged upon the inner face of the wall of the radiator adjacent said opening, and means for adjusting said retaining element and base toward and away from one another including a flange formed on said retaining element and having threaded engagement with said boss.

3. In a temperature indicator for radiators and the like, the combination with a radiator having an opening formed in the wall thereof, of a base abutting the outer face of the radiator wall about the opening and having a bore opening through the bottom thereof and communicating with the opening of the radiator wall, a boss depending from the upper wall of the bore of the base, said boss having a bore formed therein opening through the upper end of the base, an indicating fluid containing tube having its lower end disposed in the bore of said boss, means at the lower end of the boss limiting downward movement of the tube in the bore, a protecting housing for the upper end of said tube carried by said base, and means for securing said base in position upon the wall of the radiator, including a member engaging the inner wall of the radiator having portions extending upwardly into the bore of the base and secured to said boss.

4. In a temperature indicator for radiators and the like, the combination with a radiator having an opening formed in the wall thereof, of a base abutting the outer face of the radiator wall about the opening and having a bore opening through the bottom thereof and communicating with the opening of the radiator wall, a boss depend-

ing from the upper wall of the bore of the base, said boss having a bore formed therein opening through the upper end of the base, an indicating fluid containing tube having its lower end disposed in the bore of said boss, means at the lower end of the boss limiting downward movement of the tube in the bore, a protecting housing for the upper end of said tube carried by said base, and means for securing said base in position upon the wall of the radiator, including a member engaging the inner wall of the radiator and having portions extending upwardly into the bore of the base and having threaded engagement with said boss. 25

5. In a temperature indicator for radiators and the like, the combination with a radiator having an opening formed in the wall thereof, of a base abutting the outer face of the radiator wall about the opening and having a bore opening through the bottom thereof and communicating with the opening of the radiator wall, a boss depending from the upper wall of the bore of the 20 base, said boss having a bore formed therein opening through the upper end of the base, an indicating fluid containing tube having its lower end disposed in the bore of said boss, means at the lower end of the boss limiting downward movement of the tube in the bore, a protecting housing for the upper end of said tube carried by said base, and means for securing said base in position upon the wall of the radiator, including a member engaging the inner wall of the radiator and having portions extending upwardly into the bore of the base and having threaded engagement with said boss. 30

25

5. In a temperature indicator for radiators and the like, the combination with a radiator having an opening formed in the wall thereof, of a base abutting the outer face of the radiator wall about the opening and having a bore opening through the bottom thereof and communicating with the opening of the radiator wall, a boss depending from the upper wall of the bore of the 20 base, said boss having a bore formed therein opening through the upper end of the base, an indicating fluid containing tube having its lower end disposed in the bore of said boss, means at the lower end of the boss limiting downward movement of the tube in the bore, a protecting housing for the upper end of said tube carried by said base, and means for securing said base in position upon the wall of the radiator, including a member engaging the inner wall of the radiator and having portions extending upwardly into the bore of the base and having threaded engagement with said boss. 35

40

5. In a temperature indicator for radiators and the like, the combination with a radiator having an opening formed in the wall thereof, of a base abutting the outer face of the radiator wall about the opening and having a bore opening through the bottom thereof and communicating with the opening of the radiator wall, a boss depending from the upper wall of the bore of the 20 base, said boss having a bore formed therein opening through the upper end of the base, an indicating fluid containing tube having its lower end disposed in the bore of said boss, means at the lower end of the boss limiting downward movement of the tube in the bore, a protecting housing for the upper end of said tube carried by said base, and means for securing said base in position upon the wall of the radiator, including a member engaging the inner wall of the radiator and having portions extending upwardly into the bore of the base and having threaded engagement with said boss. 45

In testimony whereof I hereunto affix my signature.

GLENN LOOPER.
